OBJECT MARKER

Jessie R. Matthews and William A. Davidson,
Norfolk, Va., assignors of seventeen one-hundredths to P. H. Mason, seventeen one-hundredths to W. D. Mason, and seventeen one-hundredths to J. H. Mason, all of Norfolk, Va.

Application March 29, 1945, Serial No. 585,494

6 Claims. (Cl. 91—62.5)

1

This invention relates to object markers and more particularly to devices for applying identifying marks to the corners of containers such as boxes, cartons, crates, or the like, so that the markings may easily be seen even when the containers are stacked.

Many millions of containers are now being shipped overseas for use by the armed forces. In order to facilitate routing and distribution every container must have at least two diagonally opposite corners marked with a particular color, different color markings respectively indicating different destinations or consignees. Thus one color may indicate consignment to a certain branch of the armed services, e. g. the Army, another the Navy and so on. The marking of diagonally opposite corners assures that regardless of the orientation of a container in a stack at least one corner marking can be seen. It is understood that military and naval regulations require that every container be marked in this manner.

Prior to the present invention, the standard practice followed in applying such corner markings has been to paint the corners manually with an ordinary paint brush. The corners must be painted on three triangular sides or surfaces so that the completed marking is, in effect, on the sides of a triangular pyramid. This manual operation has been time-consuming and expensive.

An object of this invention is to provide a simple and efficient device in the nature of a stamp or die by which all of the surfaces adjacent the corner of an object, e. g. a container, may be marked simultaneously by merely pressing the device into contact with the object corner portion.

Another object of the invention is to provide a device of the character referred to including a fountain, reservoir or the like for containing marking fluid which flows to a marking element, such as a pad applicator, thereby maintaining the marking element always in condition to be used without its being necessary for the operator to interrupt a series of marking operations to add fluid to the marking element.

Other objects will become apparent from a reading of the following detailed description, the appended claims, and the accompanying drawings, in which:

Figure 1 is a perspective view of part of a shipping container and a marking device embodying the invention applied thereto for transferring identifying marking material to all three sides at one corner of the container;

Figure 2 is a view similar to Figure 1 but showing the marking device withdrawn from the container with the marking material applied to the three sides at the corner of the container;

Figure 3 is a sectional view of the marking device, the section being taken on the line 3—3 of Figure 4; and

2

Figure 4 is a section on the line 4—4 of Figure 3.

The drawings show a marking device embodying the invention in one preferred form as comprising an applicator generally designated A and a handle generally designated B. In the illustrative device the applicator A is so shaped as to be adapted to mark three sides S of a pyramidal area P at the corner of an object, for example 10 a shipping container C of parallelepiped form.

The applicator A comprises a light sheath or frame 1 of metal or other suitable stiff material comprising three substantially triangular sides 2 joined or formed to the shape of an open base 15 pyramid conforming substantially to the shape of the pyramidal area P to be marked on the container C.

The sheath or frame 1 supports means for transferring marking material to the object to be marked, the material transferring means shown 20 comprising an ink pad including three sides 3 respectively lying flat against the inner faces of the three sheath sides 2. Preferably the ink pad sides 3 are resilient or compressible so as to be 25 capable of conforming to irregularities in the surfaces of the pyramidal area P of the container to be marked. To this end the ink pad includes an inner or surface flexible fabric 4 backed by 30 cushions comprising layers of felt 5, 6, and 7 which may vary in thickness as shown in Figure 3. The ink pad structure is secured to the sheath or frame 1 by means of metal strips 8 extending along the lower edges of the fabric 4 and holding the lower edges clamped against the sheath sides 35 2 by means of suitable fastening means such as rivets 9.

In use, marking material is applied to the fabric 4 in any suitable manner and the felt ink cushions 5, 6, and 7 will soak up and maintain a supply of 40 marking material as well as providing cushions for the purpose previously explained. The applicator is placed in contact with the corner of the container C in the position shown in Figure 1 and is pressed firmly against the container to transfer marking material to the container corner over substantially the whole of the pyramidal area P. The handle B is connected to the applicator A at the apex of the applicator so that when pressure is exerted on the handle all three sides of 45 the applicator will contact the associated sides S of the pyramidal area P with substantially equal force.

Preferably the marking device embodies self contained means for holding a supply of ink or 50 other marking material which can be fed to the applicator under the control of the operator so as to avoid the necessity of interrupting a series of 55 marking operations for applying the marking material to the inner sides or fabric covering 4 of the applicator. In the form shown, the handle B is hollow so as to provide an ink fountain or 60

3

reservoir 10. The handle comprises a cylinder 11 screwed as at 12 to a valve body 13 which in turn is screwed as at 14 to a flange 15 at the apex of the applicator sheath 1. The valve body 13 is formed with a duct or passage 16 for conducting ink from the fountain or reservoir 19 to a chamber 17 at the apex of the sheath 1. Flow of ink through the passage 16 may be controlled by a valve 18 normally maintained in closed position by a spring 19 and adapted to be opened by pressure on a finger piece 20. A plurality of small openings 21 arranged in a circle extend from the chamber 17 to the tops of the felt pads 5, 6, and 7.

In use, the valve 20 is opened until enough ink has flowed into the pads 5, 6, and 7 to saturate the flexible covering 4 with the marking ink. The operator then presses the applicator against the corners of the containers to be marked and opens the valve 20 periodically in order to replenish the supply of ink in the applicator.

For applying markings of different identifying colors a set of marking devices, supplied respectively with marking materials of different colors, may be provided. If the change from one color to another is not to be made often, one marking device may be used and the device may be cleaned and the fountain 10 filled with different marking material.

It will be apparent that the marking device described above provides for a very quick and efficient marking of the corners of containers or other objects without the disadvantages heretofore encountered when applying similar markings manually by means of a brush. Although the marking device shown for the purposes of illustration embodies the invention in the form now preferred, it will be apparent that changes may be made in the construction and relative arrangement of parts without departing from the invention as defined in the claims.

We claim:

1. A device for marking the three sides of a substantially pyramidal area to the corner of an object of substantially parallelepipiped form, said device comprising an applicator including three substantially triangular sides joined together so as to form the sides of an open base pyramid, the inner faces of said applicator sides being constituted by flexible material adapted to carry marking material and to transfer said marking material to said object pyramidal area when said applicator inner faces are pressed into contact with said area; and cushions backing said flexible material whereby the latter can conform to irregularities in the surface of said area so as to enable substantially the whole of said area to be marked.

2. A device for marking the three sides of a substantially pyramidal area at the corner of an object of substantially parallelepipiped form, said device comprising an applicator including three substantially triangular sides joined together so as to form the sides of an open base pyramid, said substantially triangular sides comprising ink pads the inner faces of which are adapted to transfer ink to said object pyramidal area when said device is pressed against said object with said ink pad inner faces in contact with said area.

3. A device for marking the three sides of a substantially pyramidal area at the corner of an object of substantially parallelepipiped form, said device comprising an applicator including three substantially triangular sides joined together so

4

as to form the sides of an open base pyramid, said substantially triangular sides comprising ink pads the inner faces of which are adapted to transfer ink to said object pyramidal area when said device is pressed against said object with said ink pad inner faces in contact with said area; a fountain reservoir attached to said applicator; and duct means for conducting ink from said fountain reservoir to said ink pads.

10 4. A device for marking the three sides of a substantially pyramidal area at the corner of an object of substantially parallelepipiped form, said device comprising an applicator including three substantially triangular sides joined together so as to form the sides of an open base pyramid, said substantially triangular sides comprising ink pads the inner faces of which are adapted to transfer ink to said object pyramidal area when said device is pressed against said object with said ink pad inner faces in contact with said area; a fountain reservoir attached to said applicator; duct means for conducting ink from said fountain reservoir to said ink pads; and a valve 20 for controlling flow of ink from said fountain reservoir to said ink pads.

15 5. A device for marking the three sides of a substantially pyramidal area at the corner of an object of substantially parallelepipiped form, said device comprising an applicator including three substantially triangular sides joined together so as to form the sides of an open base pyramid, said substantially triangular sides comprising ink pads the inner faces of which are adapted to transfer ink to said object pyramidal area when said device is pressed against said object with said ink pad inner faces in contact with said area; and a handle secured to said applicator at the apex of said pyramid whereby pressing on said handle will press said ink pads against the object with substantially equal force.

20 6. A device for marking the three sides of a substantially pyramidal area at the corner of an object of substantially parallelepipiped form, said device comprising an applicator including three substantially triangular sides joined together so as to form the sides of an open base pyramid, said substantially triangular sides comprising ink pads the inner faces of which are adapted to transfer ink to said object pyramidal area when said device is pressed against said object with said ink pad inner faces in contact with said area; and a handle secured to said applicator at the apex of said pyramid whereby pressing on said handle will press said ink pads against the object with substantially equal force, said handle being hollow and adapted to contain a supply of ink for said pads.
